UNITED STATES PATENT OFFICE.

LINFORD SPEARING STILES, OF BROOKLYN, NEW YORK.

WATER-GAS APPARATUS.

Application filed June 23, 1921. Serial No. 479,725.

To all whom it may concern:

Be it known that I, LINFORD SPEARING STILES, a citizen of the United States, and resident of Brooklyn, county of Kings, and 5 State of New York, have invented an Improvement in Water-Gas Apparatus, of which the following is a specification.

The object of my invention is to provide an improved construction and mode of 10 operation of water gas apparatus with the purpose of increasing the output with a given size of apparatus, and especially in those cases where a reduction in the oil required for a candle power unit is reduced 15 in producing and supplying gas on a B. t. u. basis which is now coming largely into use by way of displacement of the candle power unit. By elimination of a portion of the oil heretofore employed, a very material reduc- 20 tion in the volume of gas results and consequently to maintain the maximum output from a given apparatus under the reduced use of oil in association with the water gas, it becomes necessary to change or modify 25 the internal construction of the parts heretofore constituting the carburetter and superheater or fixing chamber with a corresponding modification in the process, and it is with the special purpose of increasing the 30 output efficiency of the carburetted water gas of the lower B. t. u. standard from the same general gas apparatus heretofore in common use supplemented by modifications therein, that my invention is concerned.

35 More particularly, it is my purpose to provide means in a water gas apparatus to materially reduce the back pressure upon the gas passing from the generator through the carburetter and fixation chambers, by caus- 40 ing the gas employed in heating the said chambers to freely pass therethrough in the same direction and with the gas divided partly through the checkered brick work constituting the carburetter portion of the 45 apparatus and partly through the check- 50 ered brick work constituting the fixing chamber of the apparatus, thereby facilitat- 55 ing the blowing up process of the generator and by proper admixture of air to the gases to be burned in the carburetter and fixing chamber portions of the apparatus, more rapidly heating the same with the object of shortening the periods of running of the apparatus for a given output. The purpose of the apparatus is, furthermore, to provide a highly heated carburetting space into which

the oil is sprayed to insure thorough vaporization and incorporation with the "blue gas" supplied from the generator preliminary to the passage of the carburetted gas through 60 the highly heated checker brick work of the carburetter and fixing chamber portions of the apparatus, whereby the maximum volume of carburetted gas may be generated and handled in a minimum period of time, 65 which result, supplementing the beneficial result in the heating up state of the process, enables the output of the apparatus of a given size to be increased over that which has heretofore been possible. 70

With the above and other objects in view, the nature of which will be more fully understood from the description hereinafter, taken in connection with the drawings, the invention consists in the novel construction 75 of gas producing apparatus and mode of operation of the process conducted therein, as hereinafter more fully described and defined in the claims.

Referring to the drawings: Fig. 1 is a 80 sectional elevation of a gas apparatus embodying my improvements and adapted for the practice of my improved process; and Fig. 2 is a similar sectional elevation showing a modified construction of my improved 85 gas apparatus.

Similar letters of reference in the several figures of the drawings designate corresponding parts.

Referring more particularly to the structure shown in Fig. 1, 2 is the generator or "blue gas" producer; and arranged within the same sheet metal casing in association with the generator, but at a higher elevation, 90 chambers constituting combined carburetter and fixing chambers 19^a and 19^b are provided, a portion of the formerly employed intervening vertical division wall 15^a remaining. By suitable flues and valves the 95 gaseous products from the generator during its blowing up process may be supplied to the bottom of the combined carburetter and fixing chambers and passed upwardly therethrough to heat them, whereas the 100 water gas (blue gas) may be delivered into a chamber 19 at the top of the combined carburetter and fixing chamber where it receives oil spray, the carburetted gas passing down through the heated checker brick 105 17 and thence to the wash-box on its way to the holder. 110

The generator 2 may be of any ordinary

construction, being provided with a grate 3, ash pit 4, and charging doors or flues 5 near the top through which coal may be supplied. Air blast is supplied to the ash pit 4 by a blast pipe 6 and controlled by a valve 7. Gas may be taken off on the "up run" from the upper end of the generator by a flue 9 having a control valve 11 and on the "down run" by the flue 12 having a control valve 14, said latter flue opening from the ash pit. The generator is further provided with a steam pipe 8 opening below the grate 3 and discharging into the ash pit during the "up run" and is also provided with a steam pipe 8' discharging into the upper part of the generator during the "down run." During the generation of the water or "blue gas" whether on the "up run" or "down run," the blast from pipe 6 is shut off and steam from either pipe 8 or 8' admitted, as the case may be; but when heating up, the steam is shut off and blast turned on and the producer gas so provided is conveyed upward and carried off by flue 9. The general construction and mode of operation of the generator is well known and will need no further explanations.

Considering now the combined carburettor and fixing chamber, the same comprises the two chambered portions 19^a and 19^b filled with checker brick work 17 and provided at the bottom with a perforated arch 18 upon which the checker brick work is supported, the said perforated arch also sustaining the division wall 15^a which terminates adjacent to the top of the checker brick work, and leaving at the upper portion of the combined carburettor and fixing chamber a mixing chamber 19 in which the "blue gas" and the oil spray are commingled prior to passing downward through the checker brick work. Immediately below the perforated arch 18 and above the generator 2 is a combustion chamber 16 into which the products of combustion or producer gas from the generator is delivered through a flue 10^b under the control of a valve 11^a. Air blast is also provided in the combustion chamber 16 through a blast pipe 23 leading from a blast main 21 and having the air blast controlled by a valve 22. In this manner, the products from the generator, when being blown to incandescent condition, are burned in the combustion chamber 16 and the gases are caused to pass upward through the perforated arch and through the checker brick work 17 of both of the chambers 19^a and 19^b and thence into the chamber 19 and finally escaping through the escape flue 25 when permitted by the adjustment of the cover or valve 26. The heated gases thus circulated through the combined carburettor and fixing chamber raise the temperature of all of the checker brick work contained therein to a high state, bringing them to a

condition suitable for gasifying the oil and fixing the carburetted water gas thus provided. The "blue gas" from the generator 2 is supplied through the flues 10 and 10^a under the control of a valve 11^b, the discharge of the said "blue gas" being into the unobstructed space of the mixing chamber 19 at the top of the combined carburettor and fixing chamber into which the oil is sprayed from the nozzle 20 opening downward through the central part of the roof of the unobstructed space of the mixing chamber. When the "blue gas" is being delivered from the generator to the chamber 19, the valve 11^a, leading to the combustion chamber 16, is closed, but the valves 11 and 14 are alternately opened. In the case of the "up run" of the generator, the valve 11 is opened and the valve 14 is closed, whereupon the "blue gas," generated by the decomposition of the steam by the action of the incandescent coal, passes by flue 9 into flue 10, thence upward through flue 10^a and into the chamber 19. In the case of the "down run" of the generator, steam is admitted above the coal bed by the steam pipe 8' and in this case, the valve 11 is closed and valve 14 opened, with the result that the "blue gas" passes from the ash pit 4 through flues 12 and 13, and thence into the flue 10 and, as before, into the chamber 19. The carburetted water gas which leaves the lower part of the combined carburettor and fixing chamber passes into the combustion chamber 16 and thence through a flue 24 to the wash-box 27, and thence by flue 28 to the holder or place of storage.

During the heating up process, when the products of combustion from the generator are supplied to the combustion chamber 15 and therein burned, the gases so produced, after passing through the checker brick work of the combined carburettor and fixing chamber, may be again subjected to air blast from a pipe 23^a through which air is delivered into the chamber 19 under the control of the valve 22^a, so that the entire combustible portions of the products may be consumed before passing to the escape flue 25 and in that manner thoroughly heating the interior of the chamber 19. This additional heat in chamber 19 produced by the secondary combustion, will aid materially in vaporizing the oil spray and in a measure reduce the duty of the checker brick work in gasifying the oil. The air supplied to the air blast nozzle 23^a is conveyed through an extension pipe 21^a leading from the pipe 21 which supplies air blast to the combustion chamber 16.

It will be understood that in the operation of the apparatus just described, the resistance to the flow of the gases, both heating gas and carburetted water gas, through the combined carburettor and fixing cham-

ber, is considerably less than the same exists in the modern types of water gas apparatus wherein the carburetter and the fixing chamber are operated in series, and for this reason, the quantity of gases, whether produced when blowing up the generator or when generating water gas therein, are considerably increased in volume, during the normal operation of the apparatus, over what they were formerly in a modern gas apparatus of the same size; and consequently a greater output of gas in cubic feet is obtained with the apparatus constructed as herein set out, in a given period of time and with the same coal consumption, than has heretofore been possible wherein the carburetters and fixing chambers have been employed to operate in succession.

In a gas apparatus of the general arrangement of Fig. 1, so far as relates to the position of a generator below the carburetting and fixing chamber, the construction thereof is similar to the Williamson type of gas apparatus embodied, for example, in the apparatus set out in Letters Patent No. 767,217, dated August 9th, 1904, to Eustace; and when the same is converted into a gas system embodying my improvements, the dividing wall 15^a, heretofore between the fixing and carburetting chambers, is partly or wholly removed, whereby what formerly constituted the carburetting and fixing chambers are in direct communication at top and bottom and, therefore, act as a single unit, permitting the upward flow of the heating gases through the entire checker brick work of the interior chamber, at one time and likewise permitting the downflow of the carburetted water gas through the entire checker brick work of the interior chamber, as one operation, and thereby reducing the resistance to the flow of the gases in both directions to a minimum. The available cross sectional area for the upward and downward flow of the gases is approximately doubled with the resulting reduction in resistance, the oil which is supplied to the "blue gas" is delivered centrally of the upper chamber which has a cross sectional area greater than what has heretofore been the combined cross sections of the carburetter and fixing chamber, so that the vaporization of the oil and its thorough intermingling with the gases to be carburetted is more efficient and the oil being delivered at a central point of a circular chamber, insures the sprayed oil reaching every portion of the gases within said chamber. The structural changes between the invention shown in Fig. 1, and that which has heretofore been employed in the Williamson apparatus which is largely employed in commercial apparatus, is apparent when it is kept in mind that the carburetted gas flows downward through the carburetter and

thence upward through the fixing chamber. Another distinction in the present apparatus over the Williamson type, resides in the fact that the carburetted gas, after being thoroughly fixed, is delivered from the lower part of the combined carburetter and fixing chamber to the wash-box, whereas in the Williamson apparatus, the wash-box is arranged at the upper part of the fixing chamber. It is manifest, however, that the Williamson type of apparatus may be readily changed to meet the requirements of my invention and increase its efficiency in quantity production of a 550 B. t. u. per cubic foot standard of gas.

In this preferred construction of my invention, there is a unitary highly heated chamber performing simultaneously the combined functions of carburetter and fixing chamber, the same being provided with checker brick work of usual construction and having a cross sectional area or passage greatly in excess of what has heretofore been the cross sectional area of either the carburetter or fixing chamber where the said chambers were connected in series, as is customary in the commercial forms of water gas apparatus. By this construction, the shape of the chamber is maintained circular and is, therefore, best suited for thorough utilization of the checker brick work and with the greatest production of carburetted gas with a given size of carburetting and fixing chamber, whereby a maximum output may be obtained. The construction furthermore provides one in which the first function, namely, carburetting, is performed upon the "blue" gas to the fullest extent required, and thereafter the second function, namely, the fixing of the gas, takes place during the further continuous passage of the carburetted gas through the checker brick work, there being no restriction as to which portion is supplying the heat for carburetting of the gas and which part is for fixing purposes. By performing the two functions, carburetting and fixing, in one chamber, they automatically take place in accordance with requirements, that is to say, the function of the fixing chamber begins sooner or later in the passage of the gas, as may be required, thereby avoiding any loss of utility of the checker brick work and at all times utilizing the same with the highest efficiency. It will be further understood that as there is a direct passage through the combined carburetter and fixing chamber wherein the gases all pass in the same direction there is a tendency of a uniformity in the flow of gases through the carburetter and fixing chamber and thereby unaffected by reverse changes in the direction of flow and the consequent variation in pressures resulting therefrom.

Referring now to the modification shown

in Fig. 2, the same general arrangement of the generator in its relation to the carburetter and fixing chamber and combustion chamber between the generator and the said carburetter and fixing chamber is followed, as in Fig. 1, and also the general arrangement of the gas flue 10^a and its connection through a valve 11^b into the upper chamber of the carburetter corresponds to the corresponding parts of the structure of Fig. 1. Similarly, the arrangement of the blast pipes to the combustion chamber and carburetter are followed, but the intermediate wall 15^a is extended upward at the top, as at 15^b, as has heretofore been employed, dividing what was the chamber 19 of Fig. 1 into the two chambers 19^a and 19^b, the former being provided with the spray nozzle 20 and blast pipe 23^a and the latter provided with 20 the gas outlet 24 leading to the wash-box 27. Furthermore, the chamber 19^a is provided with an escape flue 25^a having a cover or valve 26^a, corresponding in general construction and operation to the similar parts at 25 the upper part of chamber 19^b. In this particular construction, the chamber 19^a and that containing the checker brick work below it down to the perforated arch 18 may be considered as a carburetting chamber, 30 whereas the chamber 19^b and the checker brick work below it down to the perforated arch 18 may be considered as the superheater or fixing chamber.

Below the carburetter chamber 19^a and 35 fixing chamber 19^b is a combustion chamber 16 having a perforated arch top 18, providing a free communication with the bottom portions of the carburetter and fixing chambers and for supporting the partition wall 15^b between them, said perforated arch permitting free passage of the heating gases upward through both chambers 19^a and 19^b or the carburetted water gas downward from the carburetter chamber, through 40 chamber 16 and thence upward through the fixing chamber. This combustion chamber 16 is provided with a flue 10^b through which producer gas from generator 2 is supplied under control of a valve 11^a, and is also provided with a blast flue 23 by which air blast may be supplied from a blast main 21, under control of a valve 22. Valves 22 and 11^a are either open or closed at the same time and cooperate in insuring proper combustion 45 when heating the chambers 19^a and 19^b.

The flue 9 from upper part of generator 2 opens into a return flue 10 which connects it with the flue 10^b opening into the combustion chamber 16 at a higher elevation. 50 The flue 10 is also connected by an L flue 13 with the flue 12 from the bottom of the generator and conveys water or "blue gas" alone, whereas flue 9 will at one time convey products of combustion when the generator is being blown for bringing its con-

tents to incandescence and at other times convey water or "blue gas" alone.

It will now be understood that the apparatus will operate as follows: When the generator 2 is being blown to heat up the coal, 70 the products of combustion pass by flue 9 through valve 11, thence by flues 10 and 10^b into the combustion chamber 16, the valve 11^a being open and valve 11^b being closed. The gases thus delivered into the combustion chamber 16 are supplied with air from blast pipe 23 and the heated gases thus produced are caused to pass upward through the perforated arch 18 and through the carburetted chamber and fixing chamber 75 simultaneously, and the waste gases are permitted to escape through the escape flues 25 and 25^a. In connection with this operation any unburned gases which pass through the carburetter 19^a are supplied with additional air blast from a nozzle 23 and are burned in the upper chamber of the carburetter before passing through the escape flue 25^a, so that this portion of the carburetter is brought to a high state of heat. 80 When this operation has been completed, the blast to the generator is closed off as is also the blast to the combustion chamber 16, and to the carburetted chamber 19^a the escape flues 25 and 25^a are closed, valve 11^a is closed, and valve 11^b is opened. Steam is then delivered by a steam pipe 8 to the lower part of the generator and the "blue gas" produced in the "up run" of the generator 85 passes through flue 9, valve 11, flues 10 and 10^a, through valve 11^b into the carburetting chamber 19^a, where it meets a spray of oil from nozzle 20 and is thus carburetted. The mixture of carburetted "blue gas" 90 passes downward through the carburetter 19^a into the chamber 16, thence upward through the fixing chamber 19^b and passes out by flue 24 through washer 27, and by flue 28 to the holder or other place of reception. Following the "up run" of the generator, the "down run" is performed and in doing this, the steam valve 8 is closed off, steam valve 8' at the top of the generator is open, valve 11 is closed, and valve 14 is open, and thereupon the "blue gas" generated on the "down run" passes through flues 12 and 13 into flue 10 and continues up to the carburetter, as before. 105

In this modified construction, the resistance to the heating gases is reduced to a minimum, as in the case of Fig. 1, but the resistance to the water gas in passing through the carburetter and superheater in succession and by the reversed direction of travel is somewhat greater, than in the case of Fig. 1, and for that reason is not so desirable. The highly heated condition of the oil spray chamber of the carburetter is found equally in this modification, as in Fig. 1. The reversed action in 110 115 120 125 130

the heating gases and water gas in passing through the carburetter is also similar in the modification to that carried on in the preferred construction of Fig. 1, though 5 this does not apply to the action through the superheater, as in that case, the flow is in the same direction. For the various reasons stated, I prefer the construction of Fig. 1 over that of Fig. 2, but it will be understood that the essential difference between the two constructions resides more particularly in the discontinuing of the wall extension 15^b in Fig. 1, and further in connecting the wash-box with the combustion 15 chamber 16 at the bottom of the combined carburetter and fixing chamber in Fig. 1, instead of at the upper part as in Fig. 2.

It will now be apparent that I have devised a novel and useful construction which 20 embodies the features of advantage enumerated as desirable, and while I have in the present instance shown and described the preferred embodiment thereof which has been found in practice to give satisfactory 25 and reliable results, it is to be understood that I do not restrict myself to the details, as the same are susceptible of modification in various particulars without departing from the spirit or scope of the invention.

30 Having now described my invention, what I claim as new and desire to secure by Letters Patent, is:

1. In a water gas apparatus, the combination of a generator provided with air 35 blast and steam pipes, a combined carburetter and fixing chamber arranged immediately above the generator and having a perforated arch at the extreme bottom and a single unobstructed space constituting a 40 mixing chamber at its upper end and also checker brick work supported upon the arch and extending up to the unobstructed space constituting the mixing chamber, a combustion chamber wholly above the generator 45 and arranged immediately below the perforated arch, a wash box in communication with the combustion chamber for the escape of water gas therefrom, a valve controlled escape flue from the top of the combined 50 carburetter and fixing chamber, a passage leading directly from the generator and extending upward outside of the body of the combined carburetter and fixing chamber, said passage having two separate valve controlled branch passages one communicating 55 directly with the combustion chamber and the other communicating directly with the unobstructed space constituting the mixing chamber in the upper part of the combined carburetter and fixing chamber, an air blast 60 pipe for supplying air to the combustion chamber, and an oil spray nozzle opening into said unobstructed space for spraying the oil over the checker brick work.

55 2. The invention according to claim 1,

wherein the oil spray nozzle is arranged in the central part of the roof of the unobstructed space so as to spray uniformly throughout the same and on all portions of the upper layer of the checker brickwork. 70

3. In a water gas apparatus, a generator, a combined carburetter and fixing chamber, and a wash-box, wherein the generator is provided with air blast and steam pipes, and the combined carburetter and fixing chamber comprising a chamber having a perforated arch at the bottom and checker brick work supported thereon and a single unobstructed space above the entire area of said brickwork, combined with a valve controlled escape flue from the top of the combined carburetter and fixing chamber, a combustion chamber wholly above the level of the generator and immediately below the perforated arch and provided with an air blast pipe, 75 an outlet for gas from the combustion chamber to the wash-box, a valve controlled passage leading from the generator to the combustion chamber below the perforated arch, a second valve controlled passage from the generator leading to and opening into the unobstructed space in the upper part of the combined carburetter and fixing chamber, and an oil spray nozzle also opening 80 into the said unobstructed space, and wherein further the combined carburetter and fixing chamber is provided with a blast pipe for supplying air to the unobstructed space above the checker brickwork and below the escape flue. 85

4. In a water gas apparatus, a generator, a combined carburetter and fixing chamber, and a wash-box, wherein the generator is provided with air blast and steam pipes, and the combined carburetter and fixing chamber comprising a chamber having a perforated arch at the bottom and checker brick work supported thereon and a single unobstructed space above the entire area of said brickwork, combined with a valve controlled escape flue from the top of the combined carburetter and fixing chamber, a combustion chamber wholly above the level of the generator and immediately below the perforated arch and provided with an air blast pipe, 90 an outlet for gas from the combustion chamber to the wash-box, a valve controlled passage leading from the generator to the combustion chamber below the perforated arch, a second valve controlled passage from the generator leading to and opening into the unobstructed space in the upper part of the combined carburetter and fixing chamber, and an oil spray nozzle also opening 95 into the said unobstructed space, and wherein further the cross sectional area of the interior chamber of the combined carburetter and fixing chamber is larger than the cross section of the generator chamber 100

105

110

115

120

125

leaving the generator is reduced in passing through the combined carburetting and fixing chamber.

5. In a water gas apparatus, a combined carburetter and fixing chamber comprising a casing having a combustion chamber at its bottom provided with a blast pipe at its bottom and a carburetting chamber at its top provided with oil spraying means at its 10 top, a water gas generator provided with air and steam pipes for generating water gas in reversed directions, a gas flue having separate valved communications respectively with the combustion chamber and carburet-

ting chamber and also having valved communications with the top and bottom of the generator, a wash-box communicating with the combustion chamber, and a valve controlled escape flue from the carburetting chamber. 15

6. The invention according to claim 5, wherein further, the carburetting chamber is also provided with an air blast pipe in the vicinity of the escape flue. 20

In testimony of which invention, I here- 25 unto set my hand.

LINFORD SPEARING STILES.
